(57) **CLAIM**

We claim the ornamental design for a telephone cradle, as shown and described.

DESCRIPTION

FIG. 1 is a front perspective view of a telephone cradle showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another front view, in which a telephone in broken lines is provided to illustrate unclaimed environment.

The broken lines in the figures depict portions of the telephone cradle that form no part of the claimed design.

The broken line showing of the telephone in FIG. 8 is for environmental purposes only and forms no part of the claimed design.
